A. J. MASSEY

VEHICLE SIGNAL

Filed May 26, 1922

INVENTOR.
Alexander J. Massey;
BY *Alfred H. Daehler,*
ATTORNEY.

UNITED STATES PATENT OFFICE.

ALEXANDER J. MASSEY, OF LOS ANGELES, CALIFORNIA.

VEHICLE SIGNAL.

Application filed May 26, 1922. Serial No. 563,760.

This invention relates to vehicle signals and it has for its object to provide an improved signal for use on motor vehicles and the like and whereby the operator thereof may give notice or indicate to the operators of other vehicles and pedestrians the immediate future course to be taken by the vehicle equipped with the signal, with respect to turning to right or left, stopping, or in the preferred form of the invention, even slowing down.

In accordance with the invention and in the preferred practice thereof, I provide a relatively flat housing or casing which serves as a mounting for a plurality of reciprocal signal members which are adapted for selective projection from the casing, and means for projecting and retracting the members; for the "Right" and "Left" turning signals a single member may be employed; and such member may have a display arrow head or other direction-indicating means at each end thereof and be arranged for projection at either side of the casing which preferably is provided with a horizontal stripe on its face. This horizontal stripe serves as an indicating arrow shank and when supplemented by one of the arrow heads on the turning signal member, readily conveys the idea that the vehicle is about to turn. The other indicating members may be vertically reciprocal and one of the same may bear the word "Slow" and the other the words "Stop", "Park", or other sign. A further object of the invention is to provide a signal of the character disclosed which will be relatively simple and inexpensive in construction and organization when its advantages, such as facility in installation, neatness and sightliness in appearance, ease of control, freedom from liability to get out of order or repair, and general superiority in service are considered.

With the above and other objects in view, the invention consists in the novel and useful provision, formation, combination, association and relative arrangement of parts, members and features, all as hereinafter described, shown in the drawing, and finally pointed out in claims.

In the drawing:

Figure 1 is a fragmentary rear elevation

of a motor vehicle equipped with a signal constructed and organized in accordance with the invention;

Figure 2 is a face view of the signal in detached position;

Figure 3 is an elevation showing the signal partly broken away, for clearness of illustration;

Figure 4 is an elevation showing the signal partly broken away, for clearness of illustration;

Figure 5 is a diagrammatic plan view of parts of the signal; and

Figure 6 is a transverse section on line x^2-x^2 , Figure 2.

Corresponding parts in all of the figures are designated by reference characters.

Referring with particularity to the drawing, in the embodiment of the invention shown therein, A designates a motor vehicle, B designates the casing of my improved signal, C, D and E designate, respectively, signal members, F designates controlling means for the signal member C, and G designates controlling means for the signal members D and E.

The casing B is shown as comprising a front wall 10, a rear wall 11, a top wall 12, and slotted right and left end and bottom walls 13, 14 and 15, respectively. The casing may be neatly finished as by enameling, and is shown as having a broad stripe 16 of a showy color, as for instance red, extending across its front or face 10' from end to end thereof. Such stripe 16 forms the shank portion of an indicating arrow which may be completed by supplementing the stripe with a head provided in the same color as the stripe, but upon the signal member C which is normally obscured in the casing.

The signal member C is shown as a plate 17 of sheet material, disposed in the casing B in registration with the slots 13' and 14' provided in the casing end walls and guided by ways at 17' formed in the casing B. The plate 17 is of the same length as the front of the casing B and has an arrow head 18 pointing to the right and an arrow head 19 pointing to the left, painted or otherwise formed thereon to match the stripe or shank 16 on the casing front. These arrow heads 18 and 19 may be joined by a shank 20, if

desired, or the shank 20 may be interrupted between the arrow heads, if desired. At its central portion, the plate 17 has a projecting pin 21 which is received in a slot 22^a provided in the lower end of a lever arm 22 which is pivotally mounted at its upper end in the casing as at 23.

The signal members D and E are shown as indicia-bearing plates 24 and 25, respectively, disposed in the casing in registration with the slot 15^a in the bottom wall 15. These plates 24 and 25 are guided by vertical ways 24^b and 25^b, respectively, in the casing. The plate 24 is shown as having the word "Slow" painted thereon, and the plate 25 is shown as having the word "Stop" painted thereon. The plate 24 has a projecting pin at 24^a which is received in a slot 24^b in the outer end of a lever arm 24^c pivotally mounted in the casing at 24^d and formed with gear teeth at its hub as at 24^e. The plate 25 is similarly connected and has a projecting pin at 25^a which is received in a slot 25^b in the outer end of a lever arm 25^c pivotally mounted in the casing at 25^d and formed with gear teeth at its hub as at 24^e. A rack bar 26 is slidably mounted in the casing beneath and in mesh with the teeth 24^e of the lever arm 24^c, and a similar rack bar 27 is slidably mounted in the casing beneath and in mesh with teeth 25^e of the lever arm 25^c. A cross bar 28 has its one end connected by a pin and slot device 28' with the rack bar 26 and has its other end connected by a pin and slot device 28" with the rack bar 27. Tension springs 29 and 30 extend between the plates 24 and 25, respectively, and the casing for the purpose of retracting and normally chambering such plates 24 and 25.

The controlling means F is shown as a device comprising a length of stiff metallic wire 31, guided in a tubing 32, leading from any suitable controlling device to the interior of the casing A through a suitable aperture at 32^a, to the end that the wire may be connected as at 33 to the lever arm 22. The controlling device, not shown, may be located upon the steering column of the vehicle or in any other position convenient to the operator.

The controlling means G is shown as comprising a length of stiff metallic wire 34 connected at its one end to the cross bar 28 at a point closer to the rack bar 26 than to the rack bar 27, but between such rack bars as at 34', and a guide tube 35 for the wire through which the same is led to a suitable point of control. Such point of control may be the brake pedal of the vehicle, and the connection of the wire 34 therewith may be such that upon depressing the pedal slightly the wire will be drawn outwardly sufficiently far to cause the downward and outward projection of the member 24, marked "Slow," due to the stronger pull on, and con-

sequent travel, of the rack bar 26 before the rack bar 27 moves. A further pull on the wire, however, due to further depression of the brake pedal, will cause the member 25, marked "Stop" to be also projected from the casing, and in position to cover the projected member 24, so indicating that the vehicle is to be stopped altogether, the priorly projected "Slow" signal, having indicated generally a slowing down of the vehicle. Upon release of the wire 34, the members 24 and 25 will both be automatically returned to the casing A by the springs 29 and 30.

To give a turning signal, the operator of the vehicle causes either arrow head 18 or 19 to appear at its corresponding side of the casing A by causing the plate 17 to be shifted to the right or left, by either pushing or pulling on the wire 31 through its controlling means. After such a turning signal has been given, the operator causes the retraction of the plate to its normal position behind the casing front, by a push or pull on the wire as the case may be.

Signals embodying the invention may be provided both at the rear and the front of vehicles and the same may be suitably illuminated at night as by means of an electric lamp.

Having thus disclosed my invention, I claim and desire to secure by Letters Patent:

1. A vehicle turning signal comprising a casing having an indicating portion extending from side to side thereof and representing the shank of an arrow, a normally obscured index member mounted for reciprocation in said casing to project the same at the right or left hand side thereof and an arrow head pointing to the left and adapted to form with said shank an arrow pointing toward the left when projected at the left hand side of said casing and displaying an arrow head pointing to the right and adapted to form with said shank an arrow pointing toward the right when projected at the right hand side of said casing, and means for controlling the movements of said member.

2. A vehicle turning signal comprising a casing having an indicating portion extending from side to side thereof, a member mounted for reciprocation in said casing and for projection at either side thereof in signaling action and displaying oppositely pointing indexes where it projects at opposite sides of the casing, and each of which indexes forms an extension of said indicating portion when displayed and conjointly therewith forms an index extending from side to side of the casing, and means for controlling the movements of said member.

3. A vehicle signal comprising a casing provided with slotted end and bottom walls; a signal member in registration with the slots in the end walls; a lever arm pivotally

5 mounted in said casing and connected to said signal member; controlling means whereby movement of said lever arm in one direction will project said member from the slot in one of the end walls and whereby movement of said arm in the opposite direction will project said member from the slot in the other end wall; and signal means adapted to be projected from the casing through the 10 slot in the bottom of the casing.

4. A vehicle signal comprising a casing provided with a slot in its bottom; vertical ways in said casing; signal members mounted in said ways and adapted to be projected from said casing through said slot; lever arms pivotally mounted in said casing and connected to said members and provided with gear teeth at their hubs; rack bars in mesh with said gear teeth; a cross bar connecting said rack bars; and controlling means for said signal members connected to said cross bar at a point closer to one of said rack bars than to the other of said rack bars to cause 20 one of said signal members to be projected from said casing before the other of said signal members.

5. A vehicle signal comprising a casing provided with a slot in its bottom; vertical ways in said casing; signal members mounted in said ways and adapted to be projected from said casing through said slot; lever arms pivotally mounted in said casing and connected to said members and provided with gear teeth at their hubs; rack bars in mesh with said gear teeth; a cross bar connecting said rack bars; means for normally retracting and chambering said signal members; and controlling means for said signal members connected to said cross bar at a 30 point closer to one of said rack bars than to the other of said rack bars to cause one 35 of said signal members to be projected from

said casing before the other of said signal members.

6. A vehicle signal comprising a casing 45 provided with a slot in its bottom; signal members in said casing adapted to be successively projected through said slot; and gear and rack means connected to successively project said members from said casing 50 whereby the last projected member will cover the first projected member.

7. A vehicle signal comprising a casing; signal members in said casing; and a gear and rack means connected to operate said signals; single operating means connected to said racks to project one of said signal members from said casing, said operating means being adapted and arranged that by further movement thereof in the same direction the other of said signal members will be projected from said casing so as to conceal 60 the first projected signal member from the view of a motorist viewing the first projected signal member. 65

8. A vehicle signal comprising a casing; signal members in said casing; single gear and rack means connected to operate said signals; operating means connected to said racks to project one of said signal members 70 from said casing, said operating means being adapted and arranged that by further movement thereof in the same direction the other of said signal members will be projected from said casing so as to conceal the 75 first projected signal member from the view of a motorist viewing the first projected signal member; and means for automatically returning both of said projected signal members into said casing. 80

In testimony whereof, I have signed my name to this specification.

ALEXANDER J. MASSEY.
